(57) **CLAIM**

The ornamental design for an outlet cover, as shown and described.

DESCRIPTION

FIG. 1 is a front right top perspective view of the outlet cover in a close/assembled position showing the design.

FIG. 2 is a front right top perspective view of the outlet cover in an open/unassembled position showing the design.

FIG. 3 is a front plan view of the outlet cover in a close/assembled position showing the design.

FIG. 4 is a right elevational view of the outlet cover in a close/assembled position showing the design.

FIG. 5 is a left elevational view of the outlet cover in a close/assembled position showing the design.

FIG. 6 is a back plan view of the outlet cover in a close/assembled position showing the design.

FIG. 7 is a bottom side elevational view of the outlet cover in a close/assembled position showing the design, this view and the opposite top side elevational view being mirror images.

FIG. 8 is a front plan view of the outlet cover in an open/unassembled position showing the design.

FIG. 9 is a right elevational view of the outlet cover in an open/unassembled position showing the design.

FIG. 10 is a left elevational view of the outlet cover in an open/unassembled position showing the design; and,

FIG. 11 is a back plan view of the outlet cover in an open/unassembled position showing the design.
